SUNDAE DISH HOLDER

Alfred Treff, Chicago, Ill., assignor, by mesne assignments, to Solo Cup Company, Chicago, Ill., a corporation of Delaware

Application April 13, 1951, Serial No. 220,873

1 Claim. (Cl. 65—61)

This application relates to a dish holder and it relates more particularly to an adapter designed to be gripped in position of use for conversion of a cup holder into a holder for paper dishes and the like.

At the present time, separate holders are supplied for use in supporting paper cups of various sizes and for paper dishes of various contours. This practice requires a fairly large inventory and supply of holders such that considerable space is taken up where space in the home or behind the soda fountain are at a premium. The presence of such holders of various shapes and sizes also presents an unsightly appearance and considerable material is tied up which, coupled with an extensive investment, makes this practice undesirable.

It would be preferred to have a holder which can be used interchangeably for various cup sizes or dishes so that one or two modifications can be stocked for use in all services demanded.

It is an object of this invention to accomplish this end by the use of adapters which can be temporarily joined with a specific holder for adapting the holder to a specific use.

It is another object of this invention to produce an adapter of the type described which is capable of being formed of low-cost materials, which is firmly gripped in position of use to impart an assembled relation which resists inadvertent displacement, which can be stocked in large numbers and in neatly stacked columns from which the uppermost can be removed without handling and with a minimum of effort for adjustment into the position of use, and which provides adequate support for the dish, and means for anchoring same in position of use.

These and other objects and advantages of this invention will hereinafter appear, and for purposes of illustration, but not of limitation, an embodiment of this invention is shown in the accompanying drawing, in which—

Fig. 1 is a perspective elevational view of an assembly embodying features of this invention with parts broken away more clearly to illustrate the position of various elements;

Fig. 2 is a top plan view of a dish member adapted for use in the practice of this invention;

Fig. 3 is a sectional elevational view through the assembly shown in Fig. 1;

Fig. 4 is an elevational view illustrating one method of use of the modified cup holder for securing a dish therein in position of use; and

Fig. 5 is a sectional view taken along the line 5—5 of Fig. 1.

Description of this invention will be made by way of reference to a cup holder embodying features described and claimed in my co-pending applications, Serial No. 212,133 and Serial No. 212,134, filed on February 21, 1951, now Patents No. 2,723,541 and No. 2,661,610, respectively. Briefly described, the holder, a modification of which is shown in the drawing, comprises a tubular

2

member 10 having an outwardly extending upper end portion 11 through which a cup is adapted to extend, when in position of use, and a lower end portion 12 which telescopes in fitting relation about an annular ring 13 which extends upwardly from the inner end of a ledge 14 upon which the lower end of the tubular member rests. The ledge 14 extends inwardly all around from the upper end of a tubular section 15 which extends upwardly from an outwardly flared base 16 that is adapted to rest upon a supporting surface. The upper end portion 11 of the tubular member is adapted to be dimensioned to correspond with the internal diameter of the tubular section 15 so as to permit telescoping therein to the extent limited by the ledge 14 for stacking the holders one on top of the other in an efficient and effective manner.

For gripping the outer wall of the cup when in position of use, there is provided a member in the form of a cylindrical section 17 which may be fabricated of one or two or more interfitting pieces having a lower end portion 18 adapted to seat within an annular groove 19 formed between the inner wall of the tubular section 10 and a lip 20 extending inwardly and upwardly from the upper portion of the section 13. Extending inwardly from the cylindrical section 17 and in vertically spaced apart relation are a plurality of shelves formed of resilient, highly flexible material, such as rubber, having openings in the central portion thereof which decrease in dimension from the upper shelf 21 to the lower shelf 23—the openings defining a frusto-conical shape substantially corresponding to the shape of the cup member adapted to be positioned therein but smaller than the cross-section of the cup located therein when in the position of use. As a result, when the cup is actuated into position of use, the adjacent edge portions of the gripping shelves are each turned down to effect an area of engagement between the top side of the shelves and the outside wall of the cup, thereby to increase the frictional gripping relation while distributing the force over a greater area to minimize deformation of the cup. The openings are preferably dimensioned to permit the upper portion of the inserted cup to rest on the upper edge of the cylindrical section 11 when the desired gripping relation has been established with the gripping members. It will be understood that for purposes of this invention, more than the three shelves 21, 22 and 23 can be used, but that it will be sufficient if less than three, or even one such gripping shelf formed of resilient or rubber-like material, is used to establish the desired gripping relation.

In accordance with this invention, an attachment or adapter is provided for use with a cup holder of the type described temporarily to convert the cup holder into a saucer or dish holder. For this purpose, the adapter is formed of rigid material, such as metal, plastics or the like, with an inverted frusto-conical section 30 contoured to correspond with the general outline of the cup for which the holder is adapted, so that the frusto-conical section can be inserted in the same manner as the cup into the holder, into gripping engagement with the resilient shelf or shelves 21, 22 and 23, and the outside wall of the frusto-conical section, while the upper portion thereof rests upon the upper edge 11 of the cylindrical section 10 for additional support. The frusto-conical section may have a length greater than that necessary for extending down between the gripping shelves, but it is preferred to limit same to reach the last of the gripping members so as to take full advantage of the frictional force available. The ends of the frusto-conical section are preferably allowed to remain open to facilitate cleaning and for conservation of material as well as to permit stacking, as will hereinafter be pointed out.

Integral with the upper edge of the frusto-conical sec-

tion 30 is an outwardly flared, relatively shallow, section 31, or skirt, having a slope corresponding to that of the saucer or dish member 32 adapted to be supported thereon. By leaving the upper end 33 of the frusto-conical section 30 open, the central portion of the dish may extend below the lower edge of the skirt for confinement within the upper end portion of the inverted frusto-conical section, as shown in Fig. 3.

A saucer or dish member suitable for use with an adapter of the type described may be formed of a paper blank having tapered, overlapping portions 34, as indicated in Fig. 2, for providing a flat central base 35, and upwardly and outwardly extending walls 36 integral with the edge thereof. A portion 37 of the dish extending beyond the edge of the skirt 31, when in position of use, may be turned down to establish a better seating relationship which militates against inadvertent removal by air currents or the like.

Various means may be provided in the adapter for temporarily anchoring the dish in position of use. One such anchoring means embodying features of this invention comprises one or more, and preferably about four, clips 38 arranged in equidistantly spaced-apart relation on the upper edge portion of the skirt. The clips may have one edge portion 39 secured, as by rivets 40 or other securing means, to the upper wall of the skirt portion while the opposite edge portion 41 is offset to extend circumferentially in closely spaced-apart relation with the adjacent surface of the skirt. In the anchored relation, the folds 34 of the dish member are adapted to be inserted within the space defined by the offset section 41 to militate against removal of the dish from position of use until intentionally turned to retract the fold from its confining slot.

Because of the tapered or frusto-conical contour of the adapter, it is possible to stack a large number of adapters by telescoping the frusto-conical sections into each other. When the stack is arranged with the bottom side up so as to place the frusto-conical section uppermost, assembly of the adapter into the cup holder may be effected simply by pressing the inverted cup holder downwardly over the uppermost adapter in the stack. In this manner, the uppermost adapter will be gripped by the holder and removed from the stack such that assembly can be quickly and easily effected, without requiring the operator to handle the adapter.

Similarly, a plurality of paper dishes folded or otherwise formed to shape, may be stacked in inverted relation to form a neat column 42, as shown in Fig. 4. When it is desired to position a dish in the modified cup holder, it is only necessary to invert the cup holder and place the adapter over the uppermost dish and then turn the cup holder until the folds are engaged by the clips. Then the cup holder can be removed with the adapter and dish fixed therein in position of use.

Although it is more sanitary to follow the simplified steps described, it is possible for the adapter and dish to be positioned by separately handling each, although it is best first to position the adapter and then the dish. When use thereof has been completed, the dish may be turned loose and discarded, and the adapter lifted from

the holder to withdraw the inverted frusto-conical section from between the gripping members. Because of the open structure, the adapter may be rinsed and cleansed in an expedient manner.

It will be understood that the invention herein is not limited to the shape of the dish or the size of the dish, and that numerous changes may be made in details of construction, arrangement and operation, without departing from the spirit of the invention, especially as defined in the following claim:

I claim:

In combination, a cup holder having a base, a cylindrical housing extending upwardly from the base and a plurality of resilient gripping members extending inwardly from the housing to define a frusto-conical opening the largest dimension of said opening being at the top for receiving and gripping a conically-shaped cup inserted therebetween, an adapter for temporary conversion of the cup holder into a holder for a saucer having a flat bottom wall and outwardly flared side walls extending upwardly continuously from the outer edges of the bottom wall and which said flared side walls are formed with folds, the adapter comprising a frusto-conical section having the end of smaller dimension lowermost with the end of larger dimension uppermost and dimensioned in cross-section to be received in the cup receiving opening of the cup holder in gripped relation, an annular flared rim extending outwardly and upwardly continuously from the upper edge of the frusto-conical section, and means for holding the saucer onto the adapter including a clip having one end secured to the rim while the other end portion extends circumferentially in closely spaced apart relation with the adjacent portions of the rim for receiving folds of the saucer.
